UNITED STATES PATENT OFFICE.

ISAAC GOLDBERG, OF NEW YORK, N. Y., ASSIGNOR TO HIMSELF AND LOUIS E. FRIEDMAN, OF NEW YORK, N.Y.

SLIPPER.

1,120,808.

Specification of Letters Patent. Patented Dec. 15, 1914.

Application filed December 29, 1913. Serial No. 809,163.

To all whom it may concern:

Be it known that I, ISAAC GOLDBERG, a citizen of the United States, and a resident of the city, county, and State of New York, 5 have invented certain new and useful Improvements in Slippers, of which the following is a specification.

In the slippers now in use of this type, when the same are worn a short time, the 10 vamps of the same become creased and wrinkled and collapse, spoiling the appearance and shape of the slipper and making it difficult for the insertion of the foot; and the object of this invention is to produce a 15 slipper which will remain open and fit the foot comfortably and always retain its shape and appearance.

Reference is to be had to the accompanying drawing, in which—
20 Figure 1 is a side elevation, partly in section, of a slipper provided with my improvement; Fig. 2 is a plan view of the same, partly broken away; and Fig. 3 is an enlarged sectional view on the line 3—3 of Fig. 2, looking in the direction of the arrows.

The slipper is provided with a usual sole 1 to which is secured a bottom sole 2 of carpet, leather or any other desired material. The vamp 3 at the front of the slipper is secured between the outer sole 1 and the 30 inner sole 4, and around the edge of the vamp is secured a strip 5 by means of stitches 6, forming a pocket 7 for the reception of a flat and flexible stiffener as a 35 spring 8 of steel, whalebone or other desired

material, the ends 8^a of this stiffener being flattened and extending between the inner sole 4 and outer sole 1 and being provided with perforations 9 through which pass 40 stitches 10 for securing the springs to the outer sole 1.

The spring is of sufficient flexibility to allow the vamp to be pressed down as desired, to aid in preparing the slippers for 45 transportation, etc., but as soon as pressure on the vamp is released it immediately springs back into position, thereby giving the slipper its normal shape.

Having described my invention, what I 50 claim is:

1. An article of the class described, comprising a sole, a vamp secured to said sole, a pocket secured to the upper edge of said vamp, and a stiffening spring contained in 55 said pocket, the ends of said spring being secured to said sole.

2. An article of the class described, comprising inner and outer soles and a vamp, a strip extending around the upper edge of 60 the vamp, secured to the same and forming a pocket for the reception of a spring, and a spring in said pocket, the ends of said spring extending between the inner and outer soles and being secured to the same. 65

Signed at the city, county and State of New York, this 27 day of December, 1913.

ISAAC GOLDBERG.
